PLAYPEN

Edwin O. Stanciff, Bakersfield, Calif.

Application October 26, 1951, Serial No. 253,297

6 Claims. (Cl. 256—25)

1

The present invention relates to improvements in a play pen. It consists of the combinations, constructions, and arrangement of parts, as hereinafter described and claimed.

An object of my invention is to provide a play pen affording a confining space for an infant, or youngster, the pen being fashioned without a bottom so as to conserve material. The lower edge of the pen is adapted to rest directly on the floor, or the like.

It is particularly proposed in this invention to fashion a play pen from sheet metal and tubing, thus permitting the several parts to be welded into a unitary and durable structure. Thus, the pen may be subjected to considerable abuse, and still it is sufficiently light in weight to permit it to be transported from place to place with facility and ease.

Other objects and advantages will appear as the specification continues. The novel features will be set forth in the claims hereunto appended.

Drawing

For a better understanding of the invention, reference should be had to the accompanying drawing, forming part of this application, in which:

Figure 1 is a horizontal sectional view taken through my play pen, along the plane I—I of Figure 3;

Figure 2 is an enlargement of the butt joint indicated at II in Figure 1;

Figure 3 is a side elevational view of the play pen, both sides being identical with one another;

Figures 4 and 5 are enlarged vertical sectional views taken along the planes IV—IV and V—V, respectively, of Figure 3.

While I have shown only the preferred form of my invention, it should be understood that various changes, or modifications, may be made within the scope of the annexed claims without departing from the spirit thereof.

Detailed description

In carrying my invention into practice, I provide a looped band of sheet metal, which is indicated generally at A. This band defines an upright wall having rolled lower and upper edges 10 and 11, respectively, these rolls projecting toward the outside of the loop.

The lower edge 10 is adapted to rest directly on a floor 12, or the like, and this eliminates the requirement of providing a bottom for the play pen. As shown in Figure 3, the upper edge 11 is spaced at a desired distance above the floor.

2

The confines of the loop band provides a playing area 14 in which an infant or youngster may be restricted. Inasmuch as the looped band A is made from sheet metal, cross-drafts will be prevented from striking the child while sleeping or crawling below the upper edge 11. Also, the solid wall will preclude toys from being thrown or pushed therethrough.

Referring now to Figures 1 and 2, I have shown 10 the looped band A as being made up of two sheets of material designated at A1 and A2. The end sections of these sheets are butted together to define seams 15. Upright strips 16 are secured by welding, or other suitable fastening means, 15 to the interior of the loop to overlie and conceal these seams.

As shown in Figure 2, the strips 16 are curved on their innermost faces, and have opposing upright edges 16a merging into the end sections of 20 the band without interruption. Figure 3 illustrates the strips 16 as having a length to extend between the lower and upper edges 10 and 11, respectively, of the looped band.

Moreover, the play pen includes a plurality of 25 upright tubular standards 17, which are welded, or otherwise secured, to the exterior of the looped band to extend thereabove. The lower ends 17a of these standards are arranged to rest on the floor 12, or the like, so as to obtain additional firm support for the standards.

For the purpose of increasing the overall height 30 of the confining area, a pair of spaced-apart looped tubular rails 18 are welded or secured horizontally on the standards 17 above the upper edge 11 of the band A. These rails provide hand-grasps, which may be utilized for moving the play pen from place to place. Also, they may be gripped by the child when the latter begins to stand upright.

40 In order to provide a strong joint at the seams 15, I have shown two of the standards 17 as being arranged in overlapping relation with the butted end sections of the sheets A1 and A2. These two 45 standards on the exterior of the loop, and the pair of upright strips 16 on the interior thereof, coact to form a particularly strong joint at the seams.

The entire interior of the play pen has been 50 fashioned without projections that would serve to injure a youngster. In this connection, the following structural facts are pointed out: the rolled edges 10—11 project toward the exterior of the looped band; the strips 16 merge into the 55 sheets A1 and A2 without interruption; and the

standards 17 are disposed exteriorly of the looped band A and the rails 18.

Thus a relatively light-weight play pen has been provided, which is sturdy in construction, and easily moved from place to place.

I claim:

1. In a play pen of the character described: an open-bottom loop-shaped band of imperforate sheet metal defining an upright solid-face enclosing wall; the confines of this wall providing a playing area; the band having an unobstructed lower edge adapted to rest flush with and directly on a floor, or the like, and further having an upper edge spaced above the floor; a plurality of upright standards disposed entirely outside of the playing area and being secured to the exterior of the loop band to extend thereabove; the standards abutting directly against the band to reinforce the latter; and at least one loop-shaped rail supported horizontally on the standards above the upper edge of the loop bands to increase the overall height of the confining area.

2. In a play pen of the character described: an open-bottom loop-shaped band of imperforate sheet metal defining an upright solid-face enclosing wall; the confines of this wall providing a playing area; the band having an unobstructed lower edge adapted to rest flush with and directly on a floor, or the like, and further having an upper edge spaced above the floor; a plurality of upright standards disposed entirely outside of the playing area and being secured to the exterior of the loop band to extend thereabove; and at least one loop-shaped rail supported horizontally on the standards above the upper edge of the loop band to increase the overall height of the confining area; the standards abutting directly against the exterior surface of the loop band to reinforce the latter, with the bottom ends of these standards terminating flush with the lower edge of the band and arranged to rest directly on the floor to give firm support to the standards.

3. In a play pen of the character described: a loop-shaped band of imperforate sheet metal defining an upright solid-face enclosing wall; the confines of this wall providing a playing area; the band having an unobstructed lower edge adapted to rest flush with and directly on a floor, or the like, and further having an upper edge spaced above the floor; the band defining at least one upright butt seam; and an upright strip abutting directly against and being secured to the interior of the band, and overlying the seam to reinforce and conceal the latter; this strip defining a horizontal curvature throughout its entire height on its innermost face, and having opposing upright edges merging into the interior face of the band without interruption to provide a continuous surface therewith.

4. In a play pen of the character described: a loop-shaped band of imperforate sheet metal defining an upright solid-face enclosing wall; the confines of this wall providing a playing area; the band having an unobstructed lower edge adapted to rest flush with and directly on a floor, or the like, and further having an upper edge

spaced above the floor; the band defining at least one upright butt seam; an upright strip abutting directly against and being secured to the interior of the band, and overlying the seam to reinforce and conceal the latter; this strip defining a horizontal curvature throughout its entire height on its innermost face, and having opposing upright edges merging into the interior face of the band without interruption to provide a continuous surface therewith; and an upright standard secured to the exterior of the band in overlapping relation with the butt seam of the band to reinforce and conceal this seam.

5. In a play pen of the character described: a loop-shaped band of imperforate sheet metal defining an upright solid-face enclosing wall; the confines of this wall providing a playing area; the band having an unobstructed lower edge adapted to rest flush with and directly on a floor, or the like, and further having an upper edge spaced above the floor; the band defining at least one upright butt seam; an upright strip abutting directly against and being secured to the interior of the band, and overlying the seam to reinforce and conceal the latter; this strip defining a horizontal curvature throughout its entire height on its innermost face, and having opposing upright edges merging into the interior face of the band without interruption to provide a continuous surface therewith; and an upright standard secured to the exterior of the band in overlapping relation with the butt seam of the band to reinforce and conceal this seam; the bottom ends of the standard and strip terminating flush with the lower edge of the band so as to rest directly on the floor to give firm support for the standard and strip.

6. In a play pen of the character described: a loop-shaped band of imperforate sheet metal defining an upright solid-face enclosing wall; the confines of this wall providing a playing area; the band having an unobstructed lower edge adapted to rest flush with and directly on a floor, or the like, and further having an upper edge spaced above the floor; a plurality of upright reinforcing standards disposed entirely outside of the playing area and being butted directly against and secured to the exterior of the loop band to reinforce the latter; the upper and lower edges of the band having reinforcing rolls thereon projecting outwardly of the band and disposed entirely exteriorly of the playing area, with these rolls extending between and abutting adjacent standards.
